UNITED STATES PATENT OFFICE.

JOZEPH GOCH AND JOHN BLACKOWIAK, OF CHICAGO, ILLINOIS.

CONVERTIBLE FURNITURE DEVICE, &c.

1,363,247.

Specification of Letters Patent. Patented Dec. 28, 1920.

Application filed September 23, 1920. Serial No. 412,303.

To all whom it may concern:

Be it known that we, JOZEPH GOCH, having made application for naturalization as a citizen of the United States, formerly a subject of the Czar of Russia, and JOHN BLACKOWIAK, a citizen of the United States, both residing at Chicago, in the county of Cook and State of Illinois, have invented certain new and useful Improvements in Convertible Furniture Devices, &c., of which the following is a specification.

Our invention relates to so-called combination or convertible devices with respect to chairs, tables, cradles, cribs and carrying devices of the suitcase type. Its principal objects are to provide in a relatively small and compact arrangement these various utilities. That is to say, in one arrangement of the parts the device constitutes substantially a suitcase in which articles may be stored away or transported from place to place, while in other arrangements respectively the other utilities are obtained. An important use of the device is by persons having babies or small children who may desire to travel and carry along some of the necessary or desirable equipment for the proper care of the child. In such case, the child's clothing, and the sheets, pillow and blankets for sleeping purposes, together with a large variety of other necessary articles may be placed within the device when arranged as a suitcase and easily transported. When the device is made of about the proportion of an ordinary-size suitcase, the various adjustments shown in the accompanying drawings severally constitute the device a chair, cradle, table or crib appropriate for a child, and thus the device is peculiarly valuable in situations where otherwise these instrumentalities might be wanting at the time when and place where needed, either in traveling or at the destination.

In the accompanying drawings, which form a part of this specification, Figure 1 is a perspective showing the device in suitcase form and in closed position; Fig. 2 shows the same device open; Fig. 3 shows the device arranged as a relatively low table in the full line position, and arranged as a chair in the dotted line position; Fig. 4 shows the device arranged as a higher table in the full line position, and as a cradle or crib with the fabric in its dotted line position; and Fig. 5 is a sectional detail showing one of the

readily applicable and removable holding pins or studs about to be forced into holding position.

The device illustrated comprises a pair of substantially U-shaped interfitting frame members A and B consisting respectively of the members 10, 11 and 12, and 13, 14 and 15, the frame B being adapted to interfit within the frame A, as well shown in Fig. 1, these frames being pivotally connected together by the bolt 16, the sides of the frames being maintained in spaced-apart relation by the bar 17, which is shown cylindrical, but which may be of other shapes. The ends of the frame A project beyond the ends of the frame B and beyond the roller 17 to form feet on which the suitcase device may rest, as shown in Fig. 1. These frame parts will ordinarily be made of sheet metal.

The flexible covering 20 of leather or fabric is permanently secured at one end to the cross-piece 21, which is part of the frame B, as by rivets 22, the leather or fabric passing over the roller 17 and being wound upon the roller 23, which has pintles 19 bearing in the frame members 10 and 12 of the frame A. The roller 23 has a ratchet 24, and a pawl 25 carried by the frame there and engaging the ratchet, and holds the leather or fabric covering with its desired degree of tautness for particular uses of the device. The covering 20 is further secured to the frame by a plurality of tabs 26 at each side portion thereof, each tab carrying a snap button device 27, which may be of well-known construction, the frame parts adjacent to the tabs respectively having interlocking studs into which the snap buttons project. Such snap fasteners are well known and require no detailed description. The cover 20 may thereby be readily removed at the sides for particular adjustments or uses of the device as a whole.

Further features of construction will be described in connection with some particular uses of the device.

In Fig. 3 the device is shown in position for use as a table or bench. The frame parts A and B are held in substantially horizontal position by struts 30 and 31, secured at 32 and 33 to the frame parts and at 34 and 35 to the leg members 40 and 41. The cross member 43, pivotally mounted on the studs 34 and 35, maintains the legs against spreading or coming together. It is to be understood that corresponding parts are at the op-

posite side of the device in Fig. 3, so that a stable support is afforded for the frame members A and B in their horizontal position shown.

5 Fig. 3 also shows the adaptation of the device for use as a chair, in which case the stud 33 is removed, the frame part B is swung upward into the dotted line position shown, and the stud 33 is inserted in the 10 hole 45 in the side member of the frame B. The cover 20 may be drawn taut or loosened for the purpose of either a table or a chair in the manner already described.

15 In Fig. 4, we have shown the arrangement of the parts to constitute the device a relatively high table or crib for a child or as a rocking cradle. For this purpose we provide a pair of springs 48—48 at each 20 side of the device, the springs having ends formed to interhook with the holes 45—46 and 49—50. When the device is to be used as a higher table the cover or fabric 20 is drawn taut as illustrated, the frames A and B being held against coming closer together than as illustrated by the impingement of one side frame member against the end of the inturned flange of the other at 56. These ends are well seen in Fig. 2. According to this arrangement, the upper 30 portion of the table is free to rock under the alternate tension of the springs 48—48. The springs, being of equal strength, tend to maintain the fabric 20 in its horizontal position, and for some uses the table will 35 thus be sufficiently stable as to the upper part thereof. If, however, it be desired to make a perfectly stable top portion of the device, meaning one which will not rock on the bolt 16, the struts 30 and 31 should 40 be connected to the side members of the frames A and B, as shown by the dotted line position of one of these struts in Fig. 3.

45 When the device shown by Fig. 4 is to be used as a crib the struts 30 and 31 will be connected rigidly to the side members respectively of the frames A and B, as illustrated by the dotted line position of one of these struts in Fig. 3, and the fabric 20 will be allowed to sag, as shown by the dotted 50 line in Fig. 4. Then, if the device be desired for use as a rocking cradle, the struts 30 and 31 will be released from the holes 45 and 49, respectively, and the springs 48—48 substituted, and thereupon the upper 55 portion of the device may be rocked on the shaft 16.

60 In order that the several parts may be connected and disconnected readily, we provide a form of stud shown in Fig. 5, having a head 60 and a pair of spring leaves 61 formed with an enlarged end 62 of greater

diameter than the hole, as 45, through which the enlarged end is adapted to be forced, the parts being thus held together with sufficient rigidity for the purpose. The 65 same form of fastener is to be understood as being used at all of the places where the struts or ties are connected to the frame parts and legs of the device.

70 We claim:

1. In a convertible device of the character described the combination of a pair of substantially U-shaped frame members having material width, the frame members being hinged together at their free ends respectively, and adapted to fold together, a flexible covering secured to one frame member so as to constitute an outer side of a suitcase-like device, the other frame member having means for holding said flexible covering adjustably, and means substantially between the pivotal connections of the frame members for holding the covering substantially U-shaped when the device is in closed position.

75 2. The device of claim 1 with the addition thereto of a pair of leg members at each side of the device, each leg member being pivotally mounted on the pivotal connection of the frame members, means for holding the leg members rigidly with their ends spaced apart to provide a stable support for the device, and means associated with some of the leg members for holding the frame members in various positions relative 80 to the leg members.

85 3. The device of claim 1 with the addition thereto of a pair of leg members pivotally mounted at each side of the device on the pivotal connection for the frame members, 90 means for holding the leg members with their ends spaced apart to form a stable support for the frame members, means for holding the frame members with their normally upper portions spaced apart, and 95 spring means operatively associated with the leg members and with the frame members for holding the frame members in a substantially balanced position, said spring means being adapted to provide for rocking 100 movement of the frame members as a unit on their pivotal connections against the tension of the spring means.

105 4. The device of claim 3 in which the spring means consist of a pair of coiled tension springs at each side of the device, each spring being connected to a frame member at a place spaced from the pivoted connection thereof, the other end of each spring being connected to a leg member.

JOZEPH GOCH.

JOHN BLACKOWIAK.
